Des. 233,878
Patented Dec. 10, 1974

233,878

RACK FOR CONDIMENTS HOLDERS

Paula H. Berger, 11752 Skyline Drive, Santa Ana, Calif.
02705, and Jack A. Birnbaum, 400 W. Orangethorpe,
#117 A, Fullerton, Calif. 92632

Filed June 1, 1973, Ser. No. 366,031

Term of patent 3½ years

Int. Cl. D7—06; D6—04
U.S. Cl. D7—71

FIG. 1.

FIG. 2.

FIG. 1 is a top front perspective view of a rack for condiment holders showing the left side of our new design; and

FIG. 2 is a bottom rear perspective view thereof showing the left side, the right side being similar thereto.

We claim:

The ornamental design for a rack for condiment holders, as shown and described.
